DRAW-DISCARD DEVICE FOR CARD GAMES

Frank J. Strassner, South Orange, N. J.

Application September 24, 1949, Serial No. 5,160

Term of patent 3½ years

(Cl. D34—13)

To all whom it may concern:

Be it known that I, Frank J. Strassner, a citizen of the United States and a resident of South Orange, county of Essex and State of New Jersey, have invented a new, original, and ornamental Design for a Draw-Discard Device for Card Games, of which the following is a specification, reference being had to the accompanying drawing, forming a part thereof.

In the drawing:

I claim:

The ornamental design for a draw-discard device for card games, substantially as shown.

FRANK J. STRASSNER.
